DESIGN FOR A DRESS

Marion McCoy, St. Louis, Mo.

Application September 19, 1941, Serial No. 103,408

Term of patent 3½ years

all whom it may concern:

Be it known that I, Marion McCoy, a citizen of the United States, residing in St. Louis, in the County of St. Louis City and State of Missouri, have invented a new, original, and ornamental design for a Dress, of which the following is a specification, reference being had to the accompanying drawing, forming part thereof.

I claim:

The ornamental design for a dress, substantially as shown.

MARION MCCOY.
